(57) **CLAIM**

The ornamental design for a powered quadricycle, as shown and described.

DESCRIPTION

FIG. 1 is a front side perspective view of a powered quadricycle showing our new design;
FIG. 2 is a front view thereof;
FIG. 3 is a rear view thereof;
FIG. 4 is a left side view thereof;
FIG. 5 is a right side view thereof; and
FIG. 6 is a top view thereof; and
FIG. 7 is a bottom view thereof.

The portions of the vehicle shown in broken lines are for illustrative purposes only and form no part of the claimed design.
